UNITED STATES PATENT OFFICE.

MOSES W. CARDEN, OF OPELIKA, ALABAMA.

CHAIR-OPERATED CHURN.

1,385,242.

Specification of Letters Patent.

Patented July 19, 1921.

Application filed December 9, 1919. Serial No. 343,591.

To all whom it may concern:

Be it known that I, MOSES W. CARDEN, a citizen of the United States of America, residing at Opelika, in the county of Lee and State of Alabama, have invented new and useful Improvements in Chair-Operated Churns, of which the following is a specification.

The object of the invention is to provide a chair operated churn or more particularly a churn operating chair equipped with normally inconspicuous means for supporting a churn in proper position to provide for the operation of churning with reference thereto by the rocking movement of the chair and adapted under normal conditions to perform the usual functions of a rocking chair, to the end that the one article of furniture may perform both functions interchangeably.

With this object in view the invention consists in a construction and combination of parts of which a preferred embodiment is shown in the accompanying drawing, wherein:

Figure 1 is a perspective view of the churn with the parts adjusted to receive and operatively support a churn.

Fig. 2 is a front view of the chair showing the churn supporting elements in a folded or housed position.

Fig. 3 is a side view with the parts arranged as in Fig. 2.

Fig. 4 is a perspective view of the churn supporting attachment disconnected from the chair.

Fig. 5 is a detail sectional view on the plane indicated by the line 5—5 of Fig. 3.

Fig. 6 is a detail sectional view on the plane indicated by the line 6—6 of Fig. 3.

The chair 10 in its general construction may correspond as illustrated with that of the ordinary rocker of which one of the arm rests 11 is pivotally mounted as at 12 to the back frame 13 and is free to move at its front end relative to the arm post 14 limited by a pin 15 which extends upward from the arm post through a slot 16 in the arm rest, said pin thus forming a stop to limit the swinging movement of the arm rest to prevent its complete disengagement from or removal from the seat afforded by the upper end of said standard.

A supplemental rocker frame 18 is also provided for adjustable relation with the chair frame, the same consisting of standards 19 to the lower ends of which is at-

tached the rocker 20, and a table 21 disposed in a substantially horizontal position and designed to slide between guide bars 22 and 23 of which the former may constitute the side bar of the chair seat 24. The table 21 is preferably divided to form an intermediate longitudinal slot 24 between which and secured to the guide bars 22 and 23 is arranged a block 25.

At their inner ends the elements of the table are connected by a stop bar 26 designed when the auxiliary rocker is extended, as shown in Fig. 1 to engage the lower guide bar 23 and thus limit the outward movement of the said auxiliary rocker while permitting the inner extremities of the elements of the table to extend under the chair bottom and afford a substantial brace for the structure.

The standards 19 are preferably extended above the plane of the table 21 to afford guards 27 and the churn body 28 is adapted to rest upon the table with its outer wall in contact with the guards 27 and its inner wall in contact with the uprights of the main chair frame as shown in Fig. 1, the arm rest 11 being provided with an extension or ear 29 to overlap the top of the churn body and thus hold the latter firmly seated on the table against displacement due to the rocking movement of the chair.

To secure the arm rest in this locking position with relation to the churn body a wedge 30 is employed to extend through the slot 16 in said arm rest and engage a socket 31 in the upper end of the arm standard 14.

Thus while the removal of the wedge or similar locking means will permit of the pivotal movement of the arm rest 11 sufficient to disengage the ear or extension 29 from the churn body so as to permit of the removal of the latter from the support afforded by the auxiliary rocker frame, such movement, however, being insufficient to entirely disengage the arm rest from the upper end of the arm standard so that accidental pressure applied to the arm rest will not tend to injure the joint 12, the return of said arm rest to its normal position as indicated in Fig. 1 will firmly lock the churn body in place and hold it against displacement while the rocking movement of the chair caused by the occupant in the ordinary use of that article of furniture will serve to agitate the contents of the churn body in the butter-making process.

It will also be understood that when the churn is not in use and the body is removed from the rest afforded by the auxiliary rocker the latter may be folded by sliding 5 it transversely of the main chair seat so as to arrange the standards 19 thereof in closed relation with the adjacent seat frame and rocker of the chair.

What is claimed is:

- 10 1. A rocking chair having an auxiliary rocker supported extension mounted for sliding movement thereon and provided with a table or rest for a churn body, said rocker element being provided at its outer end with means for preventing outward displacement of a churn body with reference to the rest, and a movable locking element mounted upon the chair for overlapping engagement with a churn body arranged 15 upon said seat for holding the latter in position thereon.
- 20 2. A rocking chair having a laterally movable arm rest and means for securing the

same in its normal position, and an auxiliary rocker element mounted for sliding 25 movement upon the frame of the chair at the side adjacent to said movable arm rest and consisting of a churn seat and a terminal rocker support, said arm rest having a projecting element for overlapping the 30 top of a churn body mounted upon said seat to hold the same in position thereon.

3. A rocking chair having a pivotal arm rest, means for limiting the swinging movement of the free end of said rest, means for 35 locking said rest in its normal position, and a laterally extensible auxiliary rocker mounted upon the chair frame and provided with a churn seat and a terminal rocker element for supporting the same, the pivotal arm 40 rest being adapted when in its normal position to engage and hold a churn body arranged upon said seat.

In testimony whereof I affix my signature.

MOSES W. CARDEN.
